UNITED STATES PATENT OFFICE.

ALFRED R. HODGE, OF CHICAGO, ILLINOIS.

DESIGN FOR A DOLL OR TOY.

47,259.

Specification for Design.

Patented Apr. 27, 1915.

Application filed April 13, 1914. Serial No. 831,643. Term of patent 3½ years.

To all whom it may concern:

Be it known that I, ALFRED R. HODGE, a citizen of the United States, residing at Chicago, in the county of Cook and State of Illinois, have invented a new, original, and ornamental Design for Dolls or Toys, of which the following is a specification, reference being had to the accompanying drawing, forming part thereof.

The figure is a perspective view of a doll or toy showing my new design.

I claim:

The ornamental design for a doll or toy, as shown.

ALFRED R. HODGE.

Witnesses:

ARTHUR L. SPRINKLE,
F. R. MORGAN.
